UNITED STATES PATENT OFFICE.

JOHN E. PFEFFER, OF CHICAGO, ILLINOIS, ASSIGNOR, BY MESNE ASSIGNMENTS, TO
M. W. WOOLSEY, OF CHICAGO, ILLINOIS.

OIL-BURNING APPARATUS.

Application filed August 26, 1921. Serial No. 495,672.

To all whom it may concern:

Be it known that I, JOHN E. PFEFFER, a citizen of the United States, residing at Chicago, in the county of Cook and State 5 of Illinois, have invented certain new and useful Improvements in Oil-Burning Apparatus, of which the following is a specification.

My invention relates to fuel burning apparatus and has particular reference to an apparatus in which hydrocarbon fuel can be burned or in which powdered coal may also be used and is primarily adapted for heating purposes for dwellings, apartment 15 buildings, hotels or the like as distinguished from fuel burning devices which are adapted for industrial purposes.

My improved apparatus is of the same general type as disclosed in my application 20 for liquid fuel burner, Serial No. 402,091, filed August 9, 1920, and is an improvement upon the apparatus described and claimed in this application in that a combustion pipe is provided within which the fuel is mixed 25 and partially consumed instead of consuming the fuel entirely within the furnace as set forth in the above identified application.

The primary object of my invention is the provision of a fuel burning apparatus 30 which is more efficient in operation and which obtains better combustion than the apparatus described in my former application and which is entirely automatic in its operation and which requires no attention 35 on the part of an operator when once the apparatus is put in service.

Another and further object of my invention is the provision of ignition means with the apparatus which automatically lights 40 the fuel which is supplied to the combustion pipe.

Another object of my invention is the provision of improved fuel mixing devices which contribute to the perfect combustion 45 obtained through the use of my improved burner and also affords better heating results because the fuel is more perfectly consumed and, therefore, supplies a larger number of heat units than has been possible here- 50 tofore with devices of this character.

These and other objects of my invention will be more fully and better understood by reference to the accompanying sheet of drawings, and in which—

55 Figure 1 is a detailed view partially in

section and partially in elevation of my improved fuel burning apparatus as applied to a heating furnace;

Figure 2 is a detailed plan view; and

Figure 3 is a detailed view in elevation 60 of my improved fuel supplying apparatus shown in Figure 2.

Referring now specifically to the drawings, in which like reference characters refer to like parts throughout, the furnace 10 is shown having a grate 11 located therein and a baffle plate 12 mounted upon the said grate 11, the furnace 10 having the usual combustion chamber 13 therein. A furnace door 14 is provided through which the combustion pipe hereinafter described extends into the combustion chamber 13 of the furnace. A base member 15 is provided to which an adjustable support 16 is provided, a set screw 17 being provided so that the standard 16 can be adjusted to different heights. A base plate 18 is mounted upon the upper end of the standard 16 and has a motor 19 secured thereto in any approved manner. The motor 19 has a pair of electric terminals 20 and 21 leading to any suitable source of electric power and has a longitudinally extending, centrally located shaft 22 extending therethrough, upon one end of which a blower 23 is connected and to the 85 other end of which a centrifugal pump 24 is directly connected by means of a link 25 or any other suitable means. The oil pump 24 has a fuel supply pipe 25^a leading to an oil container 26 and also has connected thereto 90 an overflow return pipe 27 which also leads to the fuel tank 26. The overflow pipe 27 leads from a relief valve 28 in the pump which is controlled by a spring, the pressure upon the relief valve being controlled 95 through the spring by means of a set screw 30 to which a lock nut 31 is mounted. The purpose of this relief valve 28 is to take care of the overflow oil from the pump back to the tank 26 so that the oil supplied to the burner is maintained at a predetermined pressure and there is no waste oil supplied to the burner. A fuel supply pipe 31 is connected to the pump 24 and leads to a combustion tube 32 which is connected to 100 the blower casing 33 in any approved manner and which extends through the furnace door into the combustion chamber 13 of the furnace 10 and has mounted on its inner end 105 an elbow 34, by means of which the flame is

directed against the baffle plate 12 or against any other portion of the furnace desired. Secured to the fuel supply pipe 31 is a screen 35 to which is secured a threaded 5 nipple 36 and to which an elbow 37 is secured, upon the end of which a spray nozzle 38 is secured by means of a nut 39, the elbow 37 being positioned inside of the combustion pipe 32 and centrally located in said 10 pipe, an opening in the end of the fuel nozzle 38 being provided so that the fuel will spread out at an angle of approximately 45°. A frusto-conical shaped member 40 is provided which is secured to the side wall of 15 the combustion tube 32, and is positioned in such tube just forward of the nozzle 38 so that the supply of air passing through the combustion tube 34 from the blower is directed inward at an angle of approximately 20 45° so that the stream of air and the supply of fuel pass through each other at approximately right angles to the direction of travel of each other, thus assuring a complete mixture of the fuel and the air. Ex- 25 tending longitudinal of the combustion pipe 32 along the side wall thereof is a pipe 41 having a burner tip 42 on the end thereof, through which a supply of gas is carried and which acts as ignition means of the fuel 30 after it has been mixed into the combustion tube 32. It will, therefore, be understood that combustion of the fuel begins a few inches forward of the cone 40 and very shortly after the air and fuel have been 35 brought into intimate relation with each other and continues in the combustion pipe 32 and through the elbow 34 and is completed in the combustion chamber 13 of the furnace 10. A spring closed cap 43 is se- 40 cured to the combustion pipe 41 so that access may be readily had to the fuel nozzle 38 and to the cone 40. A thermostatically controlled circuit breaker 44 is provided, which is mounted upon a base 45 to which 45 a thermostat 46 is secured, control wires 47 and 48 leading to the motor 19 and controlling its operation by closing or opening the circuit depending upon the temperature of the room in which the thermostat is located 50 which may be adjacent the furnace or in any other part of the building desired. An overflow pipe 49 is also provided which is connected to the baffle plate 12 and leads outwardly from the furnace, terminates 55 about a cup 50 on the end of a lever 51 which is pivotally mounted in a frame 52, the lever 51 having a counterweight 53 on its end opposite the cup 50. Electric wires 54 and 55 are provided which lead to the 60 motor 19 and which control its operation so that if for any reason the fuel is not ignited it will collect in the cup 50 which raises the counter-weight 53 and turns an electric switch which connects the wires 54 and 55, thus opening the circuit to the motor and

stopping its operation so that a supply of fuel is not pumped out into the furnace without being ignited. A member 56 secured to the blower 23 by means of a bolt 57 upon which a thumb nut 58 is provided controls the amount of air which enters the blower 23 so that a proper mixture of the fuel is maintained to insure proper combustion. In the operation of the device a current is supplied to the motor 19 through the 75 plugs 20 and 21 which are controlled by the thermostat 45, which is set at a predetermined degree of temperature so that when the lowest point is reached the motor will be supplied with an electric current which 80 immediately starts the pump and the blower in operation so that a current of air is forced through the pipe 32 past the collar 40, at the same time the fuel is supplied through the fuel nozzle 38 so that a mixture of fuel 85 is furnished and is ignited by the flame from the tip 42 which it will be noticed is just forward of the collar 40 so that the flame from the tip is protected and is not blown out by the action of the blower and 90 the fuel but ignites the fluid and combustion commences in the combustion pipe 32 which extends into the furnace so that the fuel is partially burned in the combustion pipe 32 and combustion is completed in the com- 95 bustion chamber of the furnace. When the temperature reaches a predetermined point the operation of the motor is stopped by the thermostat and the whole apparatus discontinues until the temperature has dropped 100 back to the lowest point on the thermostat and the same cycle of operations is completed.

While I have described more or less precisely the details of construction, I do not 105 wish to be understood as limiting myself thereto, as I contemplate changes in form and the proportion of parts and the substitution of equivalents as circumstances may suggest or render expedient without departing from the spirit and scope of my invention.

I claim:

1. In a liquid fuel burner, the combination of a centrally arranged rotary motor having a driving shaft extending from each side thereof, an air pump directly connected to one end of said shaft, a rotary fuel pump directly connected to the other end of said shaft, a combustion pipe connected to said air pump and extending into the combustion chamber of the furnace, a fuel supply pipe leading to said combustion pipe and discharging its contents into said pipe, a fuel discharge nozzle in said combustion pipe intermediate the ends thereof whereby fuel is discharged into air forced through the said combustion pipe by the blower, and a fuel ignition means in said combustion pipe. 115 120 125 130

2. In a liquid fuel burner, the combination of a centrally arranged rotary motor having a driving shaft extending from each side thereof, an air pump directly connected to one end of said shaft, a rotary fuel pump directly connected to the other end of said shaft, a combustion pipe connected to said air pump extending into the combustion chamber of the furnace, a fuel supply pipe leading to said combustion pipe, a nozzle on said fuel supply pipe adapted to discharge its contents into said combustion pipe, a collar in said pipe having a diagonally disposed portion for directing the air diagonally across the said pipe in front of the fuel nozzle, and a fuel ignition means in said combustion pipe adjacent the said collar.
3. In a liquid fuel burner, the combination of a centrally arranged rotary motor having a driving shaft extending from each side thereof, an air pump directly connected to one end of said shaft, a rotary fuel pump directly connected to the other end of said shaft, means for controlling the supply of air admitted to said air pump, a combustion pipe connected to said air pump and extending into the combustion chamber of the furnace, a fuel supply pipe leading to and discharging its contents into said combustion pipe intermediate its ends, means for supplying fuel to said pump, and means for igniting the said fuel in the said combustion pipe.
4. In a liquid fuel burner, the combination of a centrally arranged rotary motor having a driving shaft extending from each side thereof, an air pump directly connected to one end of said shaft, a rotary fuel pump directly connected to the other end of said shaft, means for controlling the supply of air admitted to said air pump, a combustion pipe connected to said air pump and extending into the combustion chamber of the furnace, a fuel supply pipe leading to said combustion pipe and having a nozzle thereon for discharging the fuel into said combustion pipe, means for supplying fuel to said pump, and a gas pipe extending longitudinally of said combustion pipe and having a tip thereon whereby the fuel is ignited adjacent said nozzle.
5. A liquid fuel burner comprising in combination an air pump, a combustion pipe connected to said air pump and forming a discharge conduit leading therefrom, means for discharging a liquid fuel into the combustion pipe, and ignition means located adjacent the fuel discharge means, the said fuel discharge means and ignition means being located at a point in said combustion pipe sufficiently remote from the discharge end thereof, whereby initial combustion of the fuel takes place in the said combustion pipe.
6. A liquid fuel burner comprising in combination an air pump, a combustion pipe connected to said air pump and extending into the combustion chamber of a furnace, means for forcing a liquid fuel into the said combustion pipe and discharging the said fuel into the said pipe intermediate its ends whereby a combustible mixture is formed in said pipe, a pilot light located in said combustion pipe adjacent the fuel discharge point, and means adapted to protect the flame of the said pilot light from the current of air forced through said combustion pipe by the blower.
7. A liquid fuel burner comprising in combination an air pump, a combustion pipe connected to said air pump and extending into the combustion chamber of a furnace, means for forcing a liquid fuel into the said combustion pipe and discharging the said fuel into the said pipe intermediate its ends whereby a combustible mixture is formed in said pipe, a pilot light located in said combustion pipe adjacent the fuel discharge point, and a circumferentially extending deflecting member positioned in said combustion pipe whereby the said pilot light is prevented from being blown out by the passage of air through the said combustion pipe.

Signed at Chicago, Illinois, this 23rd day of August, 1921.

JOHN E. PFEFFER.
